(57) **CLAIM**

The ornamental design for “a vaporization device,” as shown and described.

DESCRIPTION

FIG. 1 is a perspective view of a vaporization device, the vaporization device including a body;

FIG. 2 is a front view of the vaporization device of FIG. 1; FIG. 3 is a rear view of the vaporization device of FIG. 1; FIG. 4 is a right-side view of the vaporization device of FIG. 1;

FIG. 5 is a left-side view of the vaporization device of FIG. 1;

FIG. 6 is a top view of the vaporization device of FIG. 1; FIG. 7 is a bottom view of the vaporization device of FIG. 1;

FIG. 8 is a perspective view of the vaporization device of FIG. 1, a cartridge being received within a receptacle of the vaporization device;

FIG. 9 is a top view of the vaporization device of FIG. 1, the vaporization device being disposed in a container; and, FIG. 10 is a perspective view of the vaporization device of FIG. 1, the vaporization device being disposed in the container.

In the drawings, the broken lines represent unclaimed subject matter and form no part of the claimed design. In FIGS. 9 and 10, the broken lines showing the container are for environmental purposes only and form no part of the claimed design.

1 Claim, 6 Drawing Sheets
